UNITED STATES PATENT OFFICE

159,330

LIGHTNING ARRESTER

Julius Finkel, Brooklyn, N. Y.

Application August 23, 1949, Serial No. 4,664

Term of patent 14 years

(Cl. D26—1)

To all whom it may concern:

Be it known that I, Julius Finkel, a citizen of the United States, residing in the Borough of Brooklyn, in the county of Kings and State of New York, have invented a new, original, and ornamental Design for a Lightning Arrester, of which the following is a specification, reference being had to the accompanying drawing, forming part thereof.

In the drawing:

Fig. 1 is a top perspective view of a lightning arrester showing my new design; and

Fig. 2 is a bottom perspective view thereof.

I claim:

The ornamental design for a lightning arrester, substantially as shown.

JULIUS FINKEL.
